DESIGN FOR AN AUTOMOBILE HOOD ANTENNA

Van E. Thompson, Dearborn, Mich.

Application April 22, 1937, Serial No. 68,931

Term of patent 7 years

To all whom it may concern:

Be it known that I, Van E. Thompson, a citizen of the United States, residing at Dearborn, in the county of Wayne and State of Michigan, have invented a new, original, and ornamental Design for Automobile Hood Antennas, of which the following is a specification, reference being had to the accompanying drawing, forming a part thereof, in which:

Fig. 1 is a side elevational view of an automobile hood antenna showing the novel design.
Fig. 2 is a plan view of the antenna.

Fig. 3 is an enlarged rear elevational view of the antenna.

I claim:

The ornamental design for an automobile hood antenna substantially as shown.

VAN E. THOMPSON.
